UNITED STATES PATENT OFFICE.

THOMAS I. RANKIN, OF PHILADELPHIA, PENNSYLVANIA, ASSIGNOR TO THE
ABRAM COX STOVE COMPANY, OF SAME PLACE.

DESIGN FOR A RANGE.

SPECIFICATION forming part of Design No. 34,908, dated August 6, 1901.

Application filed August 27, 1900. Serial No. 28,261. Term of patent 7 years.

To all whom it may concern:

Be it known that I, THOMAS I. RANKIN, a citizen of the United States, residing in Philadelphia, Pennsylvania, have invented and produced a new and original Design for a Range, of which the following is a specification.

My design for a range is illustrated in the accompanying drawing, the figure of which represents the range in perspective.

The essential feature of the design is the peculiar ornamentation of the doors and the base of the stove.

A is the body of the stove, having a top plate *a*. B is the base of the stove, having legs *b*. C is the oven-door. D is the fire-door, and E is the ash-pit door.

The design of the base is made up of a series of shields with intertwined foliated and geometric scrolls. Prominently on each foot is a shield *b'*, and at the center of the apron of the base is a shield *b²*. Foliated and geometric scrolls *b³* *b⁴* complete the

ornamentation of the apron. The front portion of the apron *b⁵* of the base B is ornamented, as shown, with a central fan-shaped ornamentation united to the two shields at each side by foliated scrolls. 25

The oven-door C has a central shield *c*, and foliated scrolls *c'* surround this shield. 30

The fire-door D is in keeping with the oven-door, having a central shield *d* and ornamented scroll surrounding the same.

The ash-pit door E has a series of vertical ribs, with small scrolls at each side. 35

I claim—

The design for a range as herein described and as illustrated in the accompanying drawing.

In testimony whereof I have signed my name to this specification in the presence of two subscribing witnesses.

THOMAS I. RANKIN.
